United States Patent Office

Des. 227,652
Patented July 10, 1973

227,652

AIR DRILL OR SIMILAR ARTICLE

Harley E. Linthicum, Springfield, Ohio, assignor to
Carrier Corporation, Syracuse, N.Y.

Filed June 9, 1971, Ser. No. 151,634

Term of patent 14 years

Int. Cl. D8—01

U.S. Cl. D8—68

FIG. I

FIG. 2

FIG. 3

FIG. 1 illustrates a perspective view of an air drill or similar article, the reverse side, not illustrated, being identical to the illustrated side.

FIG. 2 is a bottom plan view thereof;

FIG. 3 is a front plan view thereof.

I claim:

The ornamental design for an air drill or similar article, substantially as shown.
